COMBINED DIRECT AND INDIRECT LIGHT
AND LIGHTING SYSTEMHilyard R. Robinson, Washington, D. C., and
Aksel J. C. Knudstrup, Vienna, Va.

Application February 7, 1939, Serial No. 255,118

7 Claims. (Cl. 240—81)

This invention relates to lamps, and more particularly to a lamp structure embodying means for providing indirect illumination.

An object of this invention is to provide a lamp structure including a novel reflector which is so constructed as to eliminate the glare incident to direct light rays.

Another object of this invention is to provide a lamp structure which may readily be used as a desk lamp, reading lamp, a bed lamp or for other purposes.

A further object of this invention is to provide a lamp structure which is capable of using different kinds of light sources depending upon the light intensity desired.

A still further object of this invention is to provide a lamp structure which is so constructed that irrespective of the intensity of the light source, it will provide indirect or diffused light.

Another object of this invention is to provide a lamp structure wherein the main portion of the light rays are directed either downwardly or upwardly and a small portion of the light rays are directed forwardly of the lamp.

A further object of this invention is to provide a lamp structure which can be manufactured at a relatively small cost, the structure being pleasing and attractive in appearance.

A further object of this invention is to provide a lamp structure which may be formed for the most part if not entirely out of initially plastic material.

To the foregoing objects and to others which may hereinafter appear, the invention consists of the novel construction, combination and arrangement of parts as will be more specifically referred to and illustrated in the accompanying drawings wherein are shown embodiments of the invention, but it is to be understood that changes, variations and modifications may be resorted to which fall within the scope of the invention as claimed.

In the drawings:

Figure 1 is a detail front elevation partly broken away and in section of a lamp structure according to an embodiment of this invention.

Figure 2 is a sectional view taken on the line 2—2 of Figure 1.

Figure 3 is a fragmentary sectional view taken on the line 3—3 of Figure 2.

Figure 4 is a detail front elevation partly broken away of a modified form of lamp structure, and

Figure 5 is a fragmentary sectional view taken on the line 5—5 of Figure 4.

Referring to the drawings and first to Figures 1, 2 and 3, inclusive, there is disclosed a lamp structure having a reflector constructed in transverse section on a spiral curve which is provided with a lower rear reflector portion 38 formed on a relatively short curve or radius and an upper reflector portion 39 which is formed on a relatively long radius. A light source or lamp 40 is positioned within the concave portion of the lower rear reflector member 38 and the forward upper portion of the reflector member 38 extends upwardly a distance sufficient to prevent any direct light rays from the light source 40 passing downwardly and forwardly. End wall members 41 are secured to the opposite ends of the reflector member 37, the end wall members 41 substantially following the configuration of the reflector 37 and having a straight portion 42 extending from the upper edge of the lower reflector 38 to the lower forward edge of the upper reflector 39.

An outer shield or cover 43 is disposed about the reflector 37 being held in spaced relation relative to the reflector 37 by means of bracket members 44. The covering or shield 43 is substantially arcuate in transverse section and at the lower rear edge thereof is provided with a relatively straight vertically disposed extension 45 and a forwardly extending portion or flange 46 extends forwardly of the lower edge of the extension 45. A bracing means 47 extends upwardly and forwardly of the flange 46 and is secured as at 48 to the under side of the reflector 38. The flange 46 together with the extension 47 and the lower portion of the extension 45 form a housing in the central portion of the lamp, the purpose for which will be hereinafter described.

The upper reflector portion 39 is provided forwardly of the lower reflector 38 with a pair of elongated slots 49 and the forward edge of the outer cover or shield 43 projects forwardly and downwardly a slight distance from the forward edges of the slots 49. The light rays from the light source 40 are adapted to be projected through the slots 49 and to be reflected downwardly by the inner surface of the cover or shield 43 through the space or opening 50 provided between the forward end of the cover 43 and the upper surface of the upper reflector 39.

An outlet box or reaction chamber 51 is disposed between the shield or cover 43 and the rear portion of the reflector 37. Where a fluorescent light source is used, the reaction means for the fluorescent light source is adapted to be mounted in the box or casing 51. A pair of vertically dis-

posed standards or supporting members 52 are secured at their upper ends to the housing formed by the flange 46 and the extension 47 and a pipe or conduit 53 extends upwardly from one of these standards 52 and is connected to the outlet box 51 so that the electric conductors may be extended through one of the standard members 52 and connected to the light socket holding the light source 40. The lower ends of the standard members 52 are secured as by nuts 53 to a base plate 54. The base plate 54 has a centrally disposed clamping jaw or base member 55 which is adapted to engage the upper surface of a support 56. A C-shaped clamp 57 is fixed at one end to the base member 55 and this clamp 57 is provided with a threaded shaft 58 carrying an adjustable or movable jaw 59. A handle 60 is secured to the lower end of the shaft 58. A switch 61 of conventional construction is adapted to be secured to the housing formed by the flange 46 and the extension 47 and is connected by the usual conductors to the light source 40.

In Figures 4 and 5, respectively, there is disclosed another form of lamp structure wherein a reflector member 62 is provided which is substantially similar in construction to the reflector 37 being formed in transverse section on a spiral curve and provided with a lower rear reflector member 63 and an upper and forwardly extending reflector member 64. The radius of the lower reflector 63 is relatively shorter than the radius of the upper reflector 64. End wall members 65 are secured to the opposite ends of the reflector 62 and a light socket 66 may be secured to one or both of the end walls 65. A second light source 67 may be positioned within the lower reflector 63 and may be in the form of a fluorescent light bulb which is adapted to be connected to a reaction member 68 disposed rearwardly of the reflector 62. The reflector 62 is provided in the central and lower portion thereof with a standard 69 which may be of any suitable length and this standard 69 is preferably hollow so as to permit the extension of conductors therethrough for connection with the socket 66 and the reaction member 68. A rear wall or plate 70 provided with a bottom wall 71 extends upwardly from the reflector 62, the bottom wall 71 being secured to the standard 69 and at its forward edge to the rear of the lower reflector 63. A forwardly projecting wall 72 extends forwardly from the upper edge of the back wall 70 and an arcuate reflector 73 extends downwardly from the flange or upper wall 72. The reflector 73 is secured at its lower edge to the rear wall 70 by means of bracket members 74 which are constructed in the form of a straight bar 75 having a right angular rear leg 76. The rear leg 76 is secured to the back wall 70 by fastening means 77. The forward end of the bar 75 is provided with an obtusely disposed extension 78 which is fixed by fastening members 79 to the lower edge of the rear upper reflector 73.

A light source 80 is disposed forwardly of the reflector 70 and is connected to a reaction member 81 which is positioned in the space or chamber 82 between the rear wall 70 and the reflector 73. The upper reflector member 64 is provided with a reflecting upper surface and at a point forwardly of the lower end of the reflector 73 the reflector 64 is provided with an elongated opening 83 so that light rays from the light sources 66 or 67 may be projected upwardly through the opening 83. Conversely, the light rays from the light

source 80 may be projected downwardly through the opening 83.

A second or intermediate arcuate upper reflector 84 is positioned forwardly of the rear upper reflector 73 and above the reflector 64. The opposite ends of the reflector 84 are secured to the end members 65 and the inner lower end of the reflector 84 terminates forwardly of the opening 83 and is positioned in spaced relation to the upper surface of the reflector 84 so that a certain degree of light will pass between the reflector 84 and the reflector 64. A forward wall or reflector plate 85 is connected at its upper edge to the upper forward edge of the reflector 84 and is secured to the end walls 65. The plate 85 is provided with a convex outer surface and a relatively long opening or slot 86 is provided in the forward or lower edge of the plate 85 so that light may pass out through the opening 86. A plurality of U-shaped bracing members 87 are secured as by fastening members 88 to the upper forward reflector 84 and by fastening members 89 to the plate 85. The bracing members 87 are provided with laterally projecting feet 90 which are secured as by fastening members 91 to the upper surface of the reflector 84. A pair of light switches 92 and 93 may be secured to the standard 69 and are adapted to be connected to the light sources in the reflectors 64 and the reflectors 73 and 84. A second light source 94 may be positioned closely adjacent the concave surface of the reflector 84 and may be used in conjunction with the light source mounted in the socket 66. Certain of the direct light rays from the light source 94 are adapted to be projected downwardly through the opening 83 and then be reflected by the reflector 62.

The lamp disclosed in Figures 1 to 3 is provided as a desk lamp and while we have shown a clamping means in the form of a C-clamp 57 for clamping the standard 52 onto the table 56, it will be understood that if desired a suitable base may be substituted for the clamping means 57. The light source 40 is adapted to project the light rays onto the two reflectors 38 and 39 and these light rays will then be reflected forwardly and downwardly. Certain of the light rays from the light source 40 will project through the openings 49 and will pass out or be reflected through the space 50 between the covering 43 and the forward portion of the upper reflector member 39. The reflector 37 together with the cover 43 may also be formed out of plastic material although if desired it may be constructed substantially entirely out of metal.

Where the lamp disclosed in Figures 4 and 5, respectively is used, either light sources in the lower reflector 62 or the upper reflector comprising the reflector members 73 and 84 may be used. Where it is desired to use the lamp shown in Figures 4 and 5, respectively as a night lamp, a light source 95 is positioned in the space between the intermediate reflector 84 and the outer reflector plate 85. The light rays from this light member 95 will be projected outwardly through the opening 86 and may also be reflected rearwardly by the reflecting inner concave surface of the plate or reflector 85. The rearwardly projected light rays will strike the upper rear reflector 73 and then be deflected in an upward direction.

It will be apparent from the foregoing that an improved lamp structure has been provided which is capable of being used for various purposes and which will provide indirect or diffused lighting.

the degree of intensity of the light depending upon the character of the light source. Where a relatively high degree of intensity of light is desired, fluorescent lamps may be mounted in 5 the sockets provided for that purpose and within the several reflectors.

What we claim is:

1. A lamp comprising a reflector having the configuration in transverse section of a spiral curve and including a lower upwardly directed reflector member having a relatively short radius and an upper downwardly directed reflector member, a light source in said lower reflector member, said upper reflector member having an 10 elongated opening therethrough whereby certain of the light rays from said light source and from said lower reflector are adapted to pass through said upper reflector member, a member above said upper reflector member in a position to intercept certain of the light rays passing through said opening, said latter member having an edge thereof spaced from the upper surface of said upper reflector member whereby certain of the 15 light rays passing through said opening are adapted to pass forwardly between said latter member and the upper reflector member, and means supporting said latter member in parallel spaced relation to the upper surface of said upper reflector member.
2. A lamp comprising a reflector having the configuration in transverse section of a spiral curve and including a lower upwardly directed reflector member having a relatively short radius and an upper downwardly directed reflector member, a light source in said lower reflector member, said upper reflector member having an elongated opening therethrough whereby certain of the light rays from said light are adapted to pass through said upper reflector member, a 20 member above said upper reflector member in a position to intercept certain of the light rays passing through said opening, said latter member having an edge thereof spaced from the upper surface of said upper reflector member whereby certain of the light rays passing through said opening are adapted to pass forwardly between said latter member and the upper reflector member, and means supporting said latter member in parallel spaced relation to the upper surface of said upper reflector member.
3. A lamp comprising a reflector having the configuration in transverse section of a spiral curve and including a lower upwardly directed reflector member having a relatively short radius and an upper downwardly directed reflector member, a light source in said lower reflector member, said upper reflector member having an elongated opening therethrough whereby certain of the light rays from said light are adapted to pass through said upper reflector member, a 25 member above said upper reflector member in a position to intercept certain of the light rays passing through said opening, said latter member having an edge thereof spaced from the upper surface of said upper reflector member whereby certain of the light rays passing through said opening are adapted to pass forwardly between said latter member and the upper reflector member, and means supporting said latter member in parallel spaced relation to the upper surface of said upper reflector member, a housing formed with said latter member and secured to said lower reflector member, and a standard secured at its upper end to said housing, the forward edge of said latter member terminating rearwardly of the forward edge of said upper reflector member.
4. A lamp comprising a reflector having the configuration in transverse section of a spiral curve and including a lower upwardly directed reflector member having a relatively short radius and an upper downwardly directed reflector member, a light source in said lower reflector member, said upper reflector member having an elongated opening therethrough whereby certain of the light rays from said light are adapted to pass through said upper reflector member, a member above said upper reflector member in a position to intercept certain of the light rays passing through said opening, said latter member having an edge thereof spaced from the upper surface of said upper reflector member whereby certain of the light rays passing through said opening are adapted to pass forwardly between said latter member and the upper reflector member, said latter member having a configuration in transverse section coincident with the configuration of said upper reflector member, means supporting said latter member in parallel spaced relation to the upper surface of said upper reflector member, a housing formed with said latter member and secured to said lower reflector member, and a standard secured at its upper end to said housing, the forward edge of said latter member terminating rearwardly of the forward edge of said upper reflector member.
5. A lamp comprising a horizontally disposed elongated reflector substantially of spiral contour in transverse section, said reflector being formed of an upper elongated downwardly directed reflecting portion and a lower upwardly directed reflecting portion of less width than, depending from, and merging at its rear into the rear end of said upper portion, a lamp arranged in the rear end terminal portion of said reflector and disposed within said lower portion, the said upper portion having an opening in the top thereof, a curved reflector member arranged over the said upper portion and acting to intercept the light rays passing through said opening and directing light rays forwardly of said upper portion, said member having an edge portion permanently spaced from the upper surface of the upper portion of the horizontal reflector, and means for supporting said horizontal reflector and said member.
6. A lamp comprising a horizontally disposed elongated reflector substantially of spiral contour in transverse section, said reflector being formed of an upper elongated downwardly directed reflecting portion and a lower upwardly directed reflecting portion of less width than, depending from, and merging at its rear into the rear end of said upper portion, a lamp arranged in the rear end terminal portion of said reflector and disposed within said lower portion, the said upper portion having an opening in the top thereof, curved reflecting means arranged over the said upper portion, said means having an edge portion permanently spaced from the upper surface of the upper portion of the horizontal reflector, means for supporting said horizontal reflector and said curved reflecting means, and means whereby rays of light are projected between the upper surface of the upper horizontal reflector and the edge portion of the curved reflecting means.

lation to the upper surface of said upper reflector member, a housing formed with said latter member and secured to said lower reflector member, and a standard secured at its upper end to said housing.

4. A lamp comprising a reflector having the configuration in transverse section of a spiral curve and including a lower upwardly directed reflector member having a relatively short radius and an upper downwardly directed reflector member, a light source in said lower reflector member, said upper reflector member having an elongated opening therethrough whereby certain of the light rays from said light are adapted to pass through said upper reflector member, a member above said upper reflector member in a position to intercept certain of the light rays passing through said opening, said latter member having an edge thereof spaced from the upper surface of said upper reflector member whereby certain of the light rays passing through said opening are adapted to pass forwardly between said latter member and the upper reflector member, said latter member having a configuration in transverse section coincident with the configuration of said upper reflector member, means supporting said latter member in parallel spaced relation to the upper surface of said upper reflector member, a housing formed with said latter member and secured to said lower reflector member, and a standard secured at its upper end to said housing, the forward edge of said latter member terminating rearwardly of the forward edge of said upper reflector member.

5. A lamp comprising a horizontally disposed elongated reflector substantially of spiral contour in transverse section, said reflector being formed of an upper elongated downwardly directed reflecting portion and a lower upwardly directed reflecting portion of less width than, depending from, and merging at its rear into the rear end of said upper portion, a lamp arranged in the rear end terminal portion of said reflector and disposed within said lower portion, the said upper portion having an opening in the top thereof, a curved reflector member arranged over the said upper portion and acting to intercept the light rays passing through said opening and directing light rays forwardly of said upper portion, said member having an edge portion permanently spaced from the upper surface of the upper portion of the horizontal reflector, and means for supporting said horizontal reflector and said member.

6. A lamp comprising a horizontally disposed elongated reflector substantially of spiral contour in transverse section, said reflector being formed of an upper elongated downwardly directed reflecting portion and a lower upwardly directed reflecting portion of less width than, depending from, and merging at its rear into the rear end of said upper portion, a lamp arranged in the rear end terminal portion of said reflector and disposed within said lower portion, the said upper portion having an opening in the top thereof, curved reflecting means arranged over the said upper portion, said means having an edge portion permanently spaced from the upper surface of the upper portion of the horizontal reflector, means for supporting said horizontal reflector and said curved reflecting means, and means whereby rays of light are projected between the upper surface of the upper horizontal reflector and the edge portion of the curved reflecting means.

7. A lamp comprising a horizontally disposed elongated reflector substantially of spiral contour in transverse section, said reflector being formed of an upper transversely elongated downwardly directed reflecting portion and a lower upwardly directed reflecting portion of less width than, depending from, and merging at its rear into the rear end of said upper portion, a lamp arranged in the lower reflecting portion, said upper 10 downwardly directed reflecting portion having an elongated opening in the top thereof and extending lengthwise thereof, and curved reflecting means arranged above said upper reflecting portion, said curved reflecting means comprising 15 a rear reflector extending upwardly from said upper reflecting portion and having the lower edge thereof disposed closely adjacent the rear

edge of said elongated opening, an intermediate reflector forwardly of said rear reflector and having the rear edge thereof disposed forwardly of said opening and spaced upwardly from the upper surface of said upper reflecting portion, a forward reflector extending upwardly from said upper reflecting portion and having its upper edge contacting with the upper edge of said intermediate reflector, the lower edge of said forward reflector being disposed in upwardly spaced relation to the 10 upper surface of said upper reflecting portion, a lamp arranged between said rear reflector and said intermediate reflector above said opening and a lamp arranged between said intermediate reflector and said forward reflector. 15
